DESIGN FOR A CONNECTING ROD

Arthur T. Britton, Santa Clara, Calif.

Application March 13, 1943, Serial No. 109,747

Term of patent 7 years

(Cl. D77—1)

To all whom it may concern:

Be it known that I, Arthur T. Britton, a citizen of the United States, residing at Santa Clara, in the county of Santa Clara and State of California, have invented a new, original, and ornamental Design for Connecting Rods, of which the following is a specification, reference being had to the accompanying drawing, forming part thereof.

Figure 1 is a front elevational view of a connecting rod showing my new design.

Figure 2 is a side elevational, and Figure 3 is a sectional view on line 3—3 of Fig. 2 looking in the direction of the arrows.

I claim:

The ornamental design for a connecting rod, as shown.

ARTHUR T. BRITTON.
